ALEX. MOSER, OF COLLEGE POINT, NEW YORK

SLICING DEVICE

Application filed March 19, 1931. Serial No. 523,659.

This invention relates to slicing apparatus, with special reference to cutters for cheese and like soft substances in block or loaf form.

One of the objects of the invention is to provide a portable, manually operable device to cut a plurality of slices in a single operation from a semi-solid mass, particularly of cheese, in any easy and convenient manner.

10 A further feature is in the provision of means whereby the slices are maintained in uniform thickness, completely severed from each other and from the bulk of the mass.

Another aim is to produce a slicing apparatus in which the cutting elements are firmly supported and tensioned to any desired extent with entire facility and without removal from the device.

15 A further feature is in the provision of means for adjusting the cutting elements of the slicer in parallel relation whereby the thickness of the group of slices may be varied.

These and other advantageous objects, which, will later appear, are accomplished 20 by the novel and practical construction and combination of parts hereinafter described and illustrated in the accompanying drawings, constituting an essential component of this disclosure, and in which:

25 Fig. 1 is a side elevational view of one complete embodiment of the invention as ready for use.

Fig. 2 is a top plan view of the same, parts being broken away to show the construction.

30 Fig. 3 is a partial bottom plan view of the cutter carrying member and cutters arranged thereon, drawn to an enlarged scale.

Fig. 4 is a perspective view of the front corner of the cutter carrying lever.

35 Fig. 5 is a fragmentary bottom plan view of a modified form of the lever showing means for adjustably spacing the cutters.

Fig. 6 is a partial side elevation, partial sectional view of the same.

40 Referring in greater detail to the drawings, Figs. 1 and 2 show a rectangular base, generally designated by the numeral 10, on which is a slightly raised platform 11 extending transversely from one edge towards the opposite edge and having its inner end

bevelled downwardly from the center to its lateral edges providing a cutter receiving face 12.

At the extreme end of the platform 11 is a slightly raised limit stop 13, a similar but higher abutment 14 being disposed along its front edge to act as a guide for the article to be sliced and which is disposed on the platform.

45 A raised bracket 15 is fixed on the opposite corner of the base 10 and pivotally mounted therein, on an elongated bearing 16, is a lever 17, having an arch 18 in its forward portion from which extend side members 19—19' to contact the base adjacent the sides of the platform 11.

50 An operating handle 20 is fixed in the front member 19 convenient of access.

Set in the lower end of the arch member 19 is a block 21, removably engaged by pins 22 and provided in its outer face with a series of shallow transverse grooves 23.

55 Above the block 21 are a plurality of studs 24 fixed in the outer face of the arch member 19, around which are trained the bights of wires 25, constituting cutters, guided by the grooves 23 and stretched over corresponding grooves in a similar block 21' set in the bottom of the arch member 19'.

60 Above the block 21 are a plurality of studs 24 fixed in the outer face of the arch member 19, around which are trained the bights of wires 25, constituting cutters, guided by the grooves 23 and stretched over corresponding grooves in a similar block 21' set in the bottom of the arch member 19'.

An angularly disposed lug 26 is integrally formed on the lever 17, near its pivot and set

therein are tapered tuning keys 27 provided with square heads on their upper extending ends to receive a wrench by which the wires

25, fixed to the pins, may be tensionally ad-

justed in the manner of piano wires.

65 It is to be noted that, due to the arrangement, each key controls the stress on a pair of wires, so that all of the sets may be quickly

set to the desired tension.

70 As the blocks 21—21' are interchangeably engaged other blocks having grooves differently distanced apart may be readily substituted to cut slices of any desired thickness.

75 However, if it be preferred, the modified form of lever arch, seen in Figs. 5 and 6, may be used, the same consisting of an arch 30 having side members 31—31' on the sides of which are outstanding lugs 32—32' provided with conically pointed set screws 33—33', 100

their points extending slightly beyond and below the ends of the side members.

In place of the interchangeable blocks before mentioned, a pair of blocks 34—34' are 5 pivoted on pins 35—35' at their centers and grooved to receive the cutter wires 25.

Obviously upon causing the screw points to impinge on the adjacent corners of the blocks 34—34' they will turn upon their 10 pivots, as best seen in Fig. 5, thereby modifying the operative distance between the adjacent parallel wires.

In operation, the material to be sliced, in the form of a loaf or block is placed on the 15 platform 11 against the guard 14 and extended to contact the stop 13, the lever and cutter wires carried by it obviously being raised.

Upon pressing the handle 20 downwardly the wires 25 sever the end of the mass extending over the bevelled portion of the platform into as many slices as there are cutter 20 wires, and if the mass be of proper consistency, cutting is accomplished with little effort, clean, smooth and uniform slices being 25 produced.

Although I have described my improvements with considerable detail and with respect to certain particular forms of my invention, I do not desire to be limited to such 30 details since many changes and modifications may well be made without departing from the spirit and scope of my invention in its broadest aspect.

Having thus described my invention, what 35 I claim as new and desire to secure by Letters Patent, is:

1. A cheese slicer comprising a base, an arched lever pivoted thereto, a plurality of cutting wires stretched across the bottom of 10 the lever arch, pivotal blocks on the ends of the arch member over which the wires are trained for adjusting the spacing of said wires, and key means for separately tensioning each pair of wires.

45 2. A slicer comprising a base having a raised platform to receive the article to be sliced, a guide on said platform, a handled lever pivoted on said base having an arched 105 portion over said platform, a series of pins fixed in said lever at its front, a series of turning keys in the rear portion of said lever, cutter wires having their bights trained over said pins and their ends secured to said keys, transversely grooved blocks pivoted at their centers to the bottoms of the arch side members, and means to adjust said blocks angularly.

55 3. A cheese slicer comprising a base, an arched lever pivoted thereto, a plurality of cutting wires stretched across the bottom of the lever arch, means for adjustably spacing the wires in parallel relation, to vary the thickness of the slices produced, said means 60 comprising pivotal blocks on the ends of the arch member over which the wires are trained,

and securing means to retain the pivoted blocks in adjusted position.

4. A slicer comprising a base having a raised platform to receive the article to be sliced, a guide on said platform, a handled lever pivoted on said base having an arched portion over said platform, a series of pins fixed in said lever at its front, a series of turning keys in the rear portion of said lever, cutter wires having their bights trained over said pins and their ends secured to said keys, means 75 for adjustably spacing the wires in parallel relation, to vary the thickness of the slices produced, said means comprising pivotal blocks on the ends of the arch member over 80 which the wires are trained, and securing means to retain the pivoted blocks in adjusted position.

Signed at New York, in the county and State of New York, this 16th day of March, 1931.

ALEX. MOSER.
